DESIGN FOR A FOOT STOOL

Hugh J. McKane, Kingston, Pa.

Application August 13, 1936, Serial No. 64,396

Term of patent 7 years

To all whom it may concern:

Be it known that I, Hugh J. McKane, a citizen of the United States, residing at Kingston, county of Luzerne, State of Pennsylvania, have invented a new, original, and ornamental Design for a Foot Stool, of which the following is a specification, reference being had to the accompanying drawing, forming a part thereof, in which Figure 1 is an end view of the foot stool showing my design, and Figure 2 is a side view of the same.

I claim:

The ornamental design for a foot stool, as shown.

HUGH J. MCKANE.
